United States Patent Office

Des. 191,748
Patented Nov. 14, 1961

191,748

TOY FIGURE

Viola M. Gale, Kansas City, Mo., assignor to Harold F. Gale, Kansas City, Mo.

Filed May 15, 1961, Ser. No. 65,159

Term of patent 7 years

(Cl. D34—4)

FIG. 1 is a front elevational view of a toy figure, showing my new design.

FIG. 2 is a side elevational view thereof; and

FIG. 3 is a rear elevational view of a toy figure.

I claim:

The ornamental design for a toy figure as shown.
